COLLAPSIBLE THREAD FEEDING APPLIANCE
FOR SEWING MACHINESRobert Picciano, Bronx, and Irving Abramowitz,
Brooklyn, N. Y.

Application January 12, 1951, Serial No. 205,756

9 Claims. (Cl. 112—218)

1

This invention relates to new and useful improvements in sewing machine attachments; and, more particularly, the aim is to provide a novel and valuable thread feeding appliance for use in connection with a home sewing machine thereby to make possible the supply of one or more continuous threads each many times the length of that wound on the usual wooden spool. A continuous thread of a length many times that at last mentioned is commonly wound on a conical shell of cardboard, papier-mâché or the like, and these windings of thread are known in the sewing, knitting and kindred art as cones.

The present invention proposes, for use in combination with a sewing machine table top, an adjustable telescopic stand, which in use will be highly efficient in coacting with one or a plurality of cones then on said table top, by guiding the threads therefrom to the sewing machine; but which between uses may be quickly and easily collapsed relative to a suitable support and down into a compartment below said table top.

A feature of the invention is that, with the sewing machine, as aforesaid a domestic or home one, of the type having a lowerable sewing head and also having one or more hinged extension leaves to be swung down parallel with and to overlie the sewing machine table top when the sewing head has been swung down to become lowered below said table top, said telescopic stand is so constituted that in collapsing the same it may be so much collapsed that no interference is offered thereby to full swinging down thereover of said extension leaf or leaves.

A further feature of the invention is that a special carrier is afforded for each cone and its shell, and a mounting means for each of said carriers is partially carried by the latter and partially carried by the sewing machine table top, for securely yet readily removably mounting a plurality of cones in thread supply position following upward and outward swinging of said extension leaf or leaves and raising of the sewing machine head for upward projection in working position above the said table top; in this connection the arrangement being such that when said carriers are removed from the said table top, as between uses of the sewing machine, no interference is offered by said mounting means to swinging down thereover of said extension leaf or leaves.

Various other features and advantages will be expressly pointed out or become apparent hereinafter.

For further comprehension of the invention,

and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a front elevation of a home sewing machine, of the kind having a lowerable sewing machine head and also having a hinged extension leaf; said leaf being shown in broken lines in the position into which it is swung preparatory to raising said head.

Fig. 2 is a fragmentary top perspective of said sewing machine, with said leaf now swung upward and then outward to extend beyond and in horizontal alignment with the sewing machine table top, with the sewing machine head (outlined in dot and dash) now in raised position, and with the telescopic stand arranged to coact with the threads from two cones on carriers now mounted on said table top.

Fig. 3 is an enlarged vertical section taken substantially on the line 3—3 of Fig. 2.

Fig. 4 is a view like Fig. 2, with said extension leaf still as in Fig. 2, but with the sewing head lowered, the cones and their carriers removed, and the telescopic stand fully collapsed.

Fig. 5, drawn to about twice the scale of Fig. 3, is a fragmentary vertical section taken on the line 5—5 of Fig. 3.

Fig. 6 illustrates on a further enlarged scale and in top perspective certain of the parts at the upper end of the telescopic stand as expanded in Fig. 5.

Fig. 7 is an axial sectional view of the cone carrier; with the cone indicated in dot and dash.

Fig. 8 is a view like Fig. 5, but with the telescopic stand fully collapsed and with the cones and their carriers removed.

Fig. 9 is an enlarged fragmentary detail section, taken axially of the telescopic stand on the line 9—9 of Fig. 5.

Fig. 10 is a horizontal section, taken on the line 10—10 of Fig. 9.

Fig. 11 is a detail section taken on the line 11—11 of Fig. 8.

Referring now to the drawings more in detail, a domestic or home type sewing machine is shown as including a main body 16, carrying upper and lower drawers 16^a and 16^b, and having a table top 17, a lowerable sewing head 18, and an extension leaf 19, hinged as at 20 to the table top 17.

The adjustable telescopic thread stand as shown has a lower section 21, an intermediate

section 22, and an upper section 23; the section 22 being longitudinally slideable in the section 21, and the section 23 being longitudinally slideable in the section 22. The bottom portion 24 of the section 21 may be finished off as shown in Figs. 3, 5 and 8. Said bottom portion 24 is suitably rigidly secured inside a sleeve 25, which sleeve is fixed in place by set-screws 26. The set-screws 26 are carried by two blocks 27 and 28 forming parts of a bracket 29, and the sleeve 25 extends through both said blocks at apertures therethrough.

The bracket 29 is fixed to the front side of a rear wall 30 forming part of said main body 16, as by screws 31.

There is a hole 32 and a hole 33 through the table top 17.

Each of said holes 32 and 33, both alike, is provided for having inserted down into the same a pin 34 fixedly dependent from a non-rotating carrier 35 for a cone of thread; each of the latter comprising as shown and as is well known a cardboard or like shell 36 on which is wound the thread 37. With said shell 36 engaged as indicated in Fig. 5 with the carrier 35, it is securely yet readily detachably carried thereby, and with the pin 34 engaged with hole 32 or 33 the carrier 35 is securely yet readily detachably carried by the table top 17.

The stand section 22 near its upper end (Fig. 9) is reduced in diameter as at 38 to have at its top a neck 39 for slidably snugly embracing the main portion of the length of the stand section 23. The said section 23 at its lower portion is outwardly flared as at 40, and said flared portion 40 is subdivided into a plurality of fingers 41 of arcuate cross-section extending longitudinally of the said section. This subdivision results from a plurality of uniformly spaced longitudinally extending slits 42. Said fingers are spring fingers, because the section 23 is made of resilient metal; and said spring fingers are resiliently biased to exert sufficient pressure against the inner surface of the section 22 to frictionally hold the section 23 at any rotational adjustment relative to the section 22 and also at any adjusted extent of upward projection beyond the upper end of the section 22.

Nevertheless, the section 23 may not ever be upwardly wholly withdrawn from the section 22 due to the said top neck 39 of the latter being of less internal diameter than the external diameter of the lower flared portion 40 of the section 23.

As indicated in the drawings (particularly see Fig. 5), the same features are present as between the sections 21 and 22; that is, the section 21 near its upper end is reduced in diameter to have at its top a neck corresponding to the neck at the top of the section 22. Also, the section 22 is outwardly flared, slotted and tensioned at its lower portion in a manner corresponding to that described for the lower portion 40 of the section 23.

The upper stand section 23 near its upper end is reduced in diameter to have at its top a neck 44 for gripping a short rod 45 at its lower slightly enlarged portion 46. Said neck at its top is crimped over as indicated in Fig. 9, and the rod 45 is tightly anchored at the top of the section 23 in any suitable way, as by brazing.

The top of the rod 45 is cylindrically enlarged as at 47 and there slotted as at 48, and the inner ends of two like swing arms 49 are pivotally mounted on the said rod and in said slot (Fig. 6).

as by a pivot pin 51. At its outer end each of said arms 49 is formed to present a thread-guiding split eye 52.

In the table top 17 is a hole 53 for the upward passage therethrough of the section 23 and the upper portion of the section 22 of the telescopic stand when said stand is fully upwardly extended as in Figs. 2, 3 and 5.

When said stand is thus extended, and the two thread cones 37 together with their carriers 35 have been mounted as shown in Fig. 5, that is, with the dependent pins 34 of said carriers inserted down into the holes 32 and 33 of the table top 17, the swing arms 49 may be swung to diverge as shown in Figs. 2 and 5 so as to dispose the split eye 52 at the outer end of each of said arms properly relative to a thread 37a from a different one of the two cones 37. One of said threads 37a may be sent to the sewing head 18, for passage relative to the usual guiding and tensioning means of the latter, to the needle; while the other of said threads 37a may be used for extension toward the bobbin winding mount, preferably after passage through suitable guiding and tensioning means also on the head 18. Said bobbin winding mount conventionally has such a location as that indicated at 54 in Fig. 3.

As sewing proceeds, the thread 37a engaging one of said eyes 52 and sent therefrom to the needle is guided by said eye so as to be smoothly unwound from the cone 37 which carries said thread, without entanglement or snagging anywhere. Also, during bobbin winding, the thread 37a engaging the other of said eyes 52 is guided therefrom so as to be smoothly unwound from the other cone 37, without entanglement or snagging anywhere.

When use of the sewing machine is to be discontinued after a period of use thereof, the two carriers 35, each with the cone 37 carried thereby and said cone's shell 36, are lifted clear of the table top 17 for storage in a convenient place, as in either or both of the drawers 16a and 16b; and, following redisposition of the two arms 49 to extend them upwardly parallel one with another and vertically above the rod 45, the telescopic stand is downwardly collapsed into a compartment 56 (Fig. 3) to become arranged as shown in Figs. 4 and 8, with the two eyes 52 in the hole 53 and with the tops of said eyes below the upper surface of the table top 17, so as not to interfere in any way with return of the extension leaf 19 from its broken line position (19a, Fig. 1) to its full line position in Fig. 1. Thus, as shown in that view, when the sewing machine is out of use, its appearance is exactly as usual, with the top of the swung over leaf 19 presenting itself as a plain and smooth table top.

As will of course be understood, the sewing head 18 will be lowered, in the direction of the arrow 55 of Fig. 3, so as to be wholly out of the way, as shown in Fig. 4, before the extension 19 is swung back to its full line position in Fig. 1. Said head 18 as lowered lies below a main opening 57 in the table top 17. A main plate portion of the head 18 is ordinarily, as shown, swingably connected to the table top 17 by a pair of curved horn type hinges 58 familiar in the cabinet making art; while also ordinarily, as shown, a panel 59 is provided at the opening 57, hinged to the table top 17 as at 60. Said panel, having a step (61, Figs. 3 and 4) is for being raised preparatory to lowering of the head 18, to clear the latter's path of downward swing, and, similarly, for being raised preparatory to raising of

the head 18. In raising the head 18, the latter is preliminarily first raised to incline its main plate portion downwardly toward the hinges 58, next the panel 59 is lowered to the horizontal, and then the head 18 is lowered to become disposed as in Fig. 3, with its front edge coming to rest on the step or ledge 61 of the panel.

Despite the fact that the telescopic stand, including the two split eyes 52, is, as above explained, wholly concealed when the sewing machine is out of use and arranged as in Fig. 1 to constitute as usual a decorative piece of furniture of the side table type, and despite the fact that even with the leaf 18 extended as at 18^a in Fig. 1 no part of said telescopic stand projects to any extent above the table top 17, with the tops of the split eyes 52 below the top of the hole 53, nevertheless, when sewing is to be resumed, the said stand may be erected and its arms 49 swung to diverge as desired, substantially instantaneously. In this connection, a feature of the invention is a shaping of said hole 53 so that the same has a forwardly upwardly inclined wall portion 62. This provides a simple, inexpensive, conveniently usable and hence highly practical means whereby, as by insertion of a screw driver or like tool down along said wall portion 62, an eye 52 may be engaged and quickly raised, by a prying thrust of said tool, and then forced to a position high enough to permit the arms 49 to be manually grasped and pulled upward to erect the telescopic stand.

While we have illustrated and described the preferred embodiment of our invention, it is to be understood that we do not limit ourselves to the precise construction herein disclosed and the right is reserved to all changes and modifications coming within the scope of the invention as defined in the appended claims.

Having thus described our invention, what we claim as new, and desire to secure by United States Letters Patent is:

1. A thread supply attachment for a home sewing machine of the type including a lowerable head, a main body having a table top provided with a main opening through which said head may be lowered, and an extension leaf hingedly connected to said table top for being swung to lie over the latter following lowering of said head, comprising, in combination with means incorporating three holes in said table top, one of said holes extending all the way through said table top and said main body having therein a compartment extending downwardly below the last-named hole, a cone carrier having a dependent projection for downward insertion in either of said holes other than the said last-named one, said carrier including a portion about which the lower end portion of a thread cone is fittable to dispose said cone upright above said support when said projection is inserted in said hole, an adjustable stand including a plurality of telescopically relatively movable sections, a thread guiding means at the upper end portion of said stand, and means for anchoring the lower end portion of said stand in said compartment to secure the stand for vertical upward erection through said last-named hole.

2. A thread supply attachment for a home sewing machine of the type including a lowerable head, a main body having a table top provided with a main opening through which said head may be lowered, and an extension leaf hingedly connected to said table top for being swung to lie over the latter following lowering of

said head, comprising, in combination with means incorporating three holes in said table top, one of said holes extending all the way through said table top and said main body having therein a compartment extending downwardly below the last-named hole, a cone carrier having a dependent projection for downward insertion in either of said holes other than the said last-named one, said carrier including a portion about which the lower end portion of a thread cone is fittable to dispose said cone upright above said support when said projection is inserted in said hole, an adjustable stand including a plurality of telescopically relatively movable sections, a thread guiding means at the upper end portion of said stand, and means for anchoring the lower end portion of said stand in said compartment to secure the stand for vertical upward erection through said last-named hole, said stand including a lower section, a middle section slidably and rotatable in said lower section and an upper section slidable and rotatable in said middle section.

3. A thread supply attachment for a home sewing machine of the type including a lowerable head, a main body having a table top provided with a main opening through which said head may be lowered, and an extension leaf hingedly connected to said table top for being swung to lie over the latter following lowering of said head, comprising, in combination with means incorporating three holes in said table top, one of said holes extending all the way through said table top and said main body having therein a compartment extending downwardly below the last-named hole, a cone carrier having a dependent projection for downward insertion in either of said holes other than the said last-named one, said carrier including a portion about which the lower end portion of a thread cone is fittable to dispose said cone upright above said support when said projection is inserted in said hole, an adjustable stand including a plurality of telescopically relatively movable sections, a thread guiding means at the upper end portion of said stand, and means for anchoring the lower end portion of said stand in said compartment to secure the stand for vertical upward erection through said last-named hole, said stand including a lower section, a middle section slidably and rotatable in said lower section and an upper section slidable and rotatable in said middle section, said thread guiding means including a swing arm carried by said stand near its top.

4. A thread supply attachment for a home sewing machine of the type including a lowerable head, a main body having a table top provided with a main opening through which said head may be lowered, and an extension leaf hingedly connected to said table top for being swung to lie over the latter following lowering of said head, comprising, in combination with means incorporating three holes in said table top, one of said holes extending all the way through said table top and said main body having therein a compartment extending downwardly below the last-named hole, a cone carrier having a dependent projection for downward insertion in either of said holes other than the said last-named one, said carrier including a portion about which the lower end portion of a thread cone is fittable to dispose said cone upright above said support when said projection is inserted in said hole, an adjustable stand including a plurality of telescopically relatively movable sections, a thread guiding

means at the upper end portion of said stand, and means for anchoring the lower end portion of said stand in said compartment to secure the stand for vertical upward erection through said last-named hole, said stand including a lower section, a middle section slidable and rotatable in said lower section and an upper section slidable and rotatable in said middle section, said thread guiding means including a swing arm carried by said stand near its top, said arm being pivoted for swing about a substantially horizontal axis.

5. A thread supply attachment for a home sewing machine of the type including a lowerable head, a main body having a table top provided with a main opening through which said head may be lowered, and an extension leaf hingedly connected to said table top for being swung to lie over the latter following lowering of said head, comprising, in combination with means incorporating three holes in said table top, one of said holes extending all the way through said table top and said main body having therein a compartment extending downwardly below the last-named hole, a cone carrier having a dependent projection for downward insertion in either of said holes other than the said last-named one, said carrier including a portion about which the lower end portion of a thread cone is fittable to dispose said cone upright above said support when said projection is inserted in said hole, an adjustable stand including a plurality of telescopically relatively movable sections, a thread guiding means at the upper end portion of said stand, and means for anchoring the lower end portion of said stand in said compartment to secure the stand for vertical upward erection through said last-named hole, said stand including a lower section, a middle section slidable and rotatable in said lower section and an upper section slidable and rotatable in said middle section, said guide means incorporating a split eye formation, there being an arm pivotally connected at one end to stand near the top of the latter, said arm carrying said formation near its other end.

6. A thread supply attachment for a home sewing machine of the type including a lowerable head, a main body having a table top provided with a main opening through which said head may be lowered, and an extension leaf hingedly connected to said table top for being swung to lie over the latter following lowering of said head, comprising, in combination with means incorporating three holes in said table top, one of said holes extending all the way through said table top and said main body having therein a compartment extending downwardly below the last-named hole, a cone carrier having a dependent projection for downward insertion in either of said holes other than the said last-named one, said carrier including a portion about which the lower end portion of a thread cone is fittable to dispose said cone upright above said support when said projection is inserted in said hole, an adjustable stand including a plurality of telescopically relatively movable sections, a thread guiding means at the upper end portion of said stand, and means for anchoring the lower end portion of said stand in said compartment to secure the stand for vertical upward erection through said last-named hole, said stand including a lower section, a middle section slidable and rotatable in said lower section and an upper section slidable and rotatable in said middle section, said guide means incorporating a split eye formation, there being an arm pivotally con-

nected at one end to said stand near the top of the latter, said arm carrying said formation near its other end, said upper section having an enlarged lower end slit at a plurality of places longitudinally of said section, said enlarged lower end being resilient to establish between said slits a plurality of spring fingers biased toward distention of said enlarged lower end and said middle section at its upper end having a neck of less internal diameter than the external diameter of the portion of said upper section just above its said enlarged lower end.

7. A thread supply attachment for a home sewing machine of the type including a lowerable head, a main body having a table top provided with a main opening through which said head may be lowered, and an extension leaf hingedly connected to said table top for being swung to lie over the latter following lowering of said head, comprising, in combination with means incorporating three holes in said table top, one of said holes extending all the way through said table top and said main body having therein a compartment extending downwardly below the last-named hole, a like plurality of cone carriers each having a downward projection for insertion in a different one of said holes other than the said last-named one, each of said carriers including a portion about which the lower end portion of a thread cone is fittable to dispose said cone upright above said support when said projection of that carrier is inserted in one of said holes, an adjustable stand including a plurality of vertical telescopically relatively movable sections, means for anchoring the lower end portion of said stand in said compartment to secure the stand for vertical upward erection through said last-named hole, and thread guiding means including a plurality of swing arms rotatively carried by said stand near its top, means for pivotally mounting said arms near the upper end of said stand, and thread guiding formations at the outer ends of said arms.

8. A thread supply attachment for a home sewing machine of the type including a lowerable head, a main body having a table top provided with a main opening through which said head may be lowered, and an extension leaf hingedly connected to said table top for being swung to lie over the latter following lowering of said head, comprising, in combination with means incorporating three holes in said table top, one of said holes extending all the way through said table top and said main body having therein a compartment extending downwardly below the last-named hole, a cone carrier having a dependent projection for downward insertion in either of said holes other than the said last-named one, said carrier including a portion about which the lower end portion of a thread cone is fittable to dispose said cone upright above said support when said projection is inserted in said hole, an adjustable stand including a plurality of telescopically relatively movable sections, a thread guiding means at the upper end portion of said stand, and means for anchoring the lower end portion of said stand in said compartment to secure the stand for vertical upward erection through said last-named hole, said last-named hole having an obliquely inclined wall portion.

9. A thread supply attachment for a home sewing machine of the type including a lowerable head, a main body having a table top provided with a main opening through which said head may be lowered, and an extension leaf hingedly

connected to said table top for being swung to lie over the latter following lowering of said head, comprising, in combination with means incorporating three holes in said table top, one of said holes extending all the way through said table top and said main body having therein a compartment extending downwardly below the last-named hole, a like plurality of cone carriers each having a downward projection for insertion in a different one of said holes other than the said last-named one, each of said carriers including a portion about which the lower end portion of a thread cone is fittable to dispose said cone upright above said support when said projection of that carrier is inserted in one of said holes, an adjustable stand including a plurality of vertical telescopically relatively movable sections, means for anchoring the lower end portion of said stand in said compartment to secure

5 the stand for vertical upward erection through said last-named hole, and thread guiding means including a plurality of swing arms rotatively carried by said stand near its top, means for pivotally mounting said arms near the upper end of said stand, and thread guiding formations at the outer ends of said arms, the said last-named hole having an obliquely inclined wall portion.
